UNITED STATES PATENT OFFICE.

MORTON A. GOODMAN, OF RICHMOND, VIRGINIA.

SHOE-BRUSH.

SPECIFICATION forming part of Letters Patent No. 469,633, dated February 23, 1892.

Application filed September 5, 1891. Serial No. 404,884. (No model.)

To all whom it may concern:

Be it known that I, MORTON A. GOODMAN, of Richmond, in the county of Henrico and State of Virginia, have invented certain new 5 and useful Improvements in Shoe-Brushes, of which the following is a specification, reference being had to the accompanying drawings, and to the letters of reference marked thereon.

- 10 In the manufacture of shoe-brushes it is customary to cover the back of the brush into which the bristles are inserted with a veneer of wood, which is either glued or tacked thereon in order to give the brush a nice finish.
- 15 From a variety of causes this veneer frequently becomes detached, thus spoiling the brush before it becomes worn out. My invention is designed to remedy this defect and otherwise improve the construction of brushes of
- 20 this class, at the same time reducing the cost of their manufacture; and it consists in the several details of construction and arrangement of parts, all as hereinafter fully set forth in the specification and pointed out in the claim.

25 In the drawings, Figure 1 is a perspective view of my improved brush. Fig. 2 is a vertical transverse section on the line $x-x$, Fig. 1. Fig. 3 is a side elevation of the metal cover detached, partly in section.

30 Similar letters of reference indicate similar parts in the respective figures.
A represents the brush proper, B the handle, and C the dauber, all secured together in the ordinary manner by the screw b , which passes through the handle into the back of the brush A, and another screw (not shown) which passes through the back of the dauber C and the end of the handle B into the back 35 of the brush A. The bristles a are inserted in and secured to the wooden back a' in the usual manner. Instead, however, of using a veneer of wood to cover and protect the securing devices I employ a metal cover D. This 40 cover is of one piece and shaped by suitable dies to form a pocket, into which the wooden

back a' fits snugly. The blanks from which the covers D are formed are provided on opposite sides with extensions d d' , which, when the wooden back a' is within the cover, are 50 bent over onto the outer face of the wooden back and securely hold it in place. These extensions are best seen in Figs. 2 and 3. The cover D is also provided with two ribs d' d'' , which project outwardly therefrom in such 55 position as to engage the opposite sides of the handle B and hold it against lateral movement, thereby relieving the strain on the screw b to a great extent and so preventing the handle from becoming loose. The cover is also 60 provided with a hole d^2 for the passage of the screw b . The ribs d' and hole d^2 may be formed simultaneously with the operation of shaping the cover and with the same dies.

I prefer to use tin as the material from 65 which to construct the covers D, as it can be japanned or otherwise treated to give it a nice appearance and finish. I do not, however, wish to limit myself to the use of such metal, as any other ductile sheet metal could be employed. I have also found that compressed paper-pulp may be advantageously used for the covers.

In practice I find that the metal cover D can be attached to the back of the brush in 75 much less time than is necessary to tack or glue a veneer of wood thereon, and as the metal cover can be produced as cheaply as the veneer the saving of labor reduces materially the cost of producing the brush.

Having described my invention, I claim—

In a brush, a back and a metal cover therefor having flanged sides and turned-under edges, the back resting in a pocket in the cover, said cover having, further, raised ribs 85 upon its top, combined with a handle secured to the back and cover and resting between the ribs of the latter, substantially as set forth.

MORTON A. GOODMAN. [L. S.]
